UNITED STATES PATENT OFFICE.

FRITZ FREI, OF BERNE, SWITZERLAND.

ELECTRIC HEATING DEVICE FOR PLUNGING.

1,401,686.

Specification of Letters Patent. Patented Dec. 27, 1921.

Application filed October 16, 1920. Serial No. 417,484.

To all whom it may concern:

Be it known that I, FRITZ FREI, citizen of the Republic of Switzerland, residing at Berne, Switzerland, have invented certain 5 new and useful Improvements in an Electric Heating Device for Plunging, of which the following is a specification.

The object of this invention is the provision of an electric heating device capable 10 of being plunged in the substance to be cooked. The heating device is provided with a heating unit in form of a short tube between the walls of which the resistance wire is located to protect the resistance wire 15 and prevent contact of the latter with the liquid or other substance into which the heating device is plunged.

In the accompanying drawing wherein a practical embodiment of the invention is 20 illustrated;

Figure 1 is a side elevation, partly broken away, of the improved electric heating device;

Fig. 2 is a similar view of a slightly modified form of the device; and

Fig. 3 is an enlarged fragmentary sectional view through the body or heating unit of the device.

Referring to the drawing in detail the 30 double walled heating unit is designated by *a*; its form is here that of a hollow cylinder but it might also be oval or elliptical. The resistance wire *v*, which is clearly shown in Fig. 3, is coiled in this cylinder between 35 layers of mica said resistance wire being anchored in a body of insulating cement designated at *d*. Each tube *e* for the lead conductor *f* is introduced in an orifice provided in the inner wall of the cylinder and it is 40 then brazed in the heating unit, so that in case of overheating, the apparatus may not be damaged. In each tube *e* is the conductor *f* insulated by means of pearls or beads *g*; said conductors being utilized for leading 45 the current to the heating unit.

In the form of the invention illustrated in Fig. 1 two tubes *e* are illustrated for conducting the corresponding number of feed conductors *f* and a handle *h* is attached to the extremities of the tubes opposite the heating unit or cylinder *a*.

The form illustrated in Fig. 2 has three tubes *e* disposed at angles of 120 degrees to one another and each of the tubes is adapted 55 to receive a conductor *f*. One of the extremities of said conductors may be con-

nected to a plug socket, the two split plugs of which may be screwed off and put in one or the other hole, according to the voltage at disposal. The heating unit of said apparatus is divided into two parts which may be utilized independently one of another for 110, respectively 150 volts and which, when connected in series, may support a current till 250 volts.

The disposition of the tubes in the interior of the heating cylinder is particularly advantageous, as well with regard to the durability and rigidity of the device as regarding the facility of construction. The tubes may be brazed to the interior wall of the heating unit after said wall has been bored and the edge of the hole has been turned inwardly as indicated at *i* in Fig. 3. The tube is then introduced in the orifice and the depression *j* formed by turning the edge of the opening inwardly, and is filled by brazing; no damage of the heating unit *v* is therefore possible, the latter being then placed in a layer of insulating material and the exterior wall being put over the whole.

I claim:

1. In an electric heating device, a double walled body member, and an electrical resistance element coiled between the walls of the body member and having the convolutions thereof arranged substantially concentric with the axis of the body member.

2. In an electric heating device, a double walled body member, an electrical resistance element arranged between the walls of the body member, electrical conductors connected with said resistance element, and independent tubes receiving the several conductors and having divergent extremities connected with the body member at remote points.

3. In an electric heating device, a double walled body member, an electrical resistance element arranged between the walls of the body member, electrical conductors connected with said resistance element, independent tubes receiving the several conductors and having divergent extremities connected with the body member at remote points, and an insulating handle member carried by the extremities of the tubes opposite said body member.

4. In an electric heating device, a double walled body member having openings formed in the inner wall thereof, the edges of the openings being turned inwardly, tu-

bular members secured to the turned edges of the openings and extending from the body member, an electrical resistance element interposed between the walls of the body member, and electrical conductors connected with the resistance element and extending through the tubes.

5. In an electric heating device, a double walled body member having openings 10 formed in the inner wall thereof, the edges of the openings being turned inwardly, tubular members secured to the turned edges of the openings and extending from the body member, an electrical resistance element interposed between the walls of the body member, electrical conductors connected with the resistance element and extending through the tubes, and beads carried 15 by the portions of the conductors lying within the tubular members for preventing contact of the latter with said conductors.

6. In an electric heating device, a double walled body member, an electrical resistance element coiled in said body member and 20 having its convolutions arranged substantially concentric with the axis of said body

member, layers of insulating material introduced between the resistance element and the walls of the body member, and means anchoring the resistance element between the 30 layers of insulating material and maintaining the convolutions of the resistance element in spaced relation.

7. In an electric heating device, a body member consisting of spaced inner and outer 35 walls having sections of the edges brought together and connected, the inner wall having openings therein and having the edges of the openings turned inwardly, tubular members secured in the openings, and an 40 electric resistance element insulated from and arranged between the walls of the body member, and electrical conductors having connection with the resistance element and extending through the tubular members. 45

In testimony whereof I affix my signature in presence of two witnesses.

FRITZ FREI.

Witnesses:

EDGAR FANE,
F. CAMPICHE.
